UNITED STATES PATENT OFFICE.

JAMES C. DAVIS, OF HINSDALE, ILLINOIS, ASSIGNOR TO AMERICAN STEEL FOUNDRIES, OF NEW YORK, N. Y., A CORPORATION OF NEW JERSEY.

REGENERATOR.

1,124,870.

Specification of Letters Patent. Patented Jan. 12, 1915.

Application filed March 23, 1914. Serial No. 826,532.

To all whom it may concern:

Be it known that I, JAMES C. DAVIS, a citizen of the United States, and resident of Hinsdale, in the county of Cook and State 5 of Illinois, have invented certain new and useful Improvements in Regenerators, of which the following is a specification.

My invention relates to air or gas regenerators and has particular reference to 10 a novel baffle plate construction.

In the operation of open hearth furnaces it is a well known practice to regenerate either or both the gas and air prior to admitting the same into the combustion space 15 the arrangement being such that the flow of gases is reversed at intervals allowing the products of combustion to pass through and transfer portions of their heat to a regenerator which heat will later be transmitted 20 to air or gas passing through such regenerator in the reverse direction.

In the later development of open hearth furnaces it has been found desirable to use comminuted coal, this substance being 25 blown into the furnace in such manner as to suitably combine with oxygen to form a combustible mixture. While this makes a not undesirable fuel there is of necessity a residue of ash which is carried into the 30 down-takes and deposits in the checker-work of the regenerators. As ordinarily constructed this seriously interferes with the operation of the regenerators and as no provision is made for cleaning the checker- 35 work the point is soon reached when the furnace must be shut down for repairs.

My invention contemplates the construction of the regenerator chamber on a somewhat different principle. In my construction 40 I provide a regenerator chamber within which a plurality of baffles are located, these baffles being constructed of a material which will absorb heat from the outgoing gases, and, such outgoing gases being 45 compelled to follow a tortuous path, will transfer the required amount of heat to the baffles. In order to provide an increased radiating surface I prefer to construct the baffles with alternate bricks projecting for 50 a portion of their length from the plane of the wall. Thus the superficial area in contact with the outgoing gases is very

largely increased and made comparable to the area presented by the usual checker-work.

55

The invention will be more readily understood by reference to the accompanying drawings, wherein,

Figure 1 is a vertical, longitudinal section through a regenerator constructed in 60 accordance with my invention; Fig. 2 is a section on the line 2—2 of Fig. 1, and Fig. 3 is a horizontal section through the construction shown in Figs. 1 and 2.

Referring more particularly to the accompanying drawings, it will be seen that my regenerator may consist of side and end walls 10 and 11, the side walls being provided with suitable manholes 12, at intervals near the bottom thereof and with similar manholes 13, at a point near the top thereof. These holes are provided in order to give access to the interior of the regenerator chamber for the purpose of dislodging and removing any deposits of ash. The top 75 wall 14, may be arched or of other construction, the roof being provided with a flue opening 15, communicating with the furnace. A stack flue 16, communicates with the regenerator at the opposite end. 80

Located within the chamber formed by the walls 10, 11, and roof 14, are a plurality of baffles 17, preferably constructed of brick, the bricks being laid in such manner that portions of alternate bricks are projected 85 outside the plane of the body of the baffle, thus providing a much greater superficial area exposed to the gas or air passing through the regenerator.

As shown in Fig. 3, alternate courses of 90 bricks may consist in two and three bricks respectively, the two bricks 18, serving to outline the width of the baffle and to bind the bricks 19 in place, the bricks 19 having a portion of their length projecting outside 95 the plane of the wall, as defined by the bricks 18.

By the arrangement shown I am enabled to provide a large superficial regenerative surface in a small space and at the same 100 time am enabled to provide means for cleaning the surface without seriously interfering with the operation of the furnace.

It is obvious that the specific arrangement

of baffles need not be followed in order to secure the desired result. They might be arranged in other manners and a large area might be secured by other arrangements of the bricks. All such modifications as are within the scope of my claims I consider within the spirit of my invention.

I claim:

1. In a regenerator, the combination of walls inclosing a chamber, and baffles located in said chamber, said baffles being provided with a relatively large number of surface projections whereby an increased superficial area is secured, substantially as described.
2. In a regenerator, the combination of walls inclosing a chamber, said chamber being provided with entrance and exit openings, and baffles located in said chamber, said baffles being provided with a great number of surface projections whereby a relatively large superficial area is presented, said walls being provided with openings through which access may be had to said baffles for

the purpose of cleaning the same, substantially as described.

3. In a regenerator, the combination of walls inclosing a chamber, baffles located in said chamber, said baffles being constructed of bricks, certain of the bricks projecting outside the normal plane of the baffles and providing an increased regenerative surface, substantially as described.

4. In a regenerator, the combination of walls inclosing a chamber, baffles located in said chamber, said baffles being constructed of bricks, certain of the bricks projecting outside the normal plane of the baffles and providing an increased regenerative surface, said walls being provided with openings through which access may be had to said baffles for the purpose of cleaning the same, substantially as described.

JAMES C. DAVIS.
